UNITED STATES PATENT OFFICE

WILLIAM G. KENDALL, OF NEWARK, NEW JERSEY

VANITY CASE

Application filed October 28, 1929. Serial No. 403,070.

This invention relates to vanity cases, and has for an object to provide an improved construction wherein means are provided for receiving an ejecting tool so that a compact 5 plate may be readily ejected when either filled or empty.

Another object of the invention is to provide a vanity case which may be round, square, hexagonal or other shape, and which 10 is formed with pressed-out portions presenting grooves on the interior and ornamental beads on the exterior, the arrangement being such that a file or other instrument may be placed in the grooves and used to eject or 15 remove the compact plate without injuring the compact therein.

In the accompanying drawing,—

Figure 1 is a top plan view of a vanity case 20 disclosing an embodiment of the invention, the lid being shown open;

Figure 2 is a side view of the structure shown in Figure 1;

Figure 3 is an enlarged fragmentary sectional view through Figure 1 on the line 25 3—3;

Figure 4 is a view similar to Figure 1 but showing a slightly modified construction;

Figure 5 is a sectional view through Figure 30 4 on the line 5—5, the same being on an enlarged scale;

Figure 6 is a fragmentary sectional view similar to Figure 5 but showing another formation wherein the groove does not reach to the top of the upstanding wall.

Referring to the accompanying drawings by numerals, 1 indicates the body of a vanity case, and 2 the cover or lid connected to the body 1 in any suitable manner, as for instance, by the hinge 3. The body 1 has been shown 40 round or circular, but so far as the invention is concerned, it could be made irregular and of any shape desired. In forming the body 1 pressed-out portions 4 are provided which, in the particular illustrations shown in the 45 drawing, consist of two, although if desired, a greater number could be provided, or even a less number without departing from the spirit of the invention.

As shown particularly in Figure 2, the 50 pressed-out portions 4 merge into the pressed-

in portions 5, said pressed-in portions 5 forming what are commonly known as nibs 6 shown particularly in Figure 3. Nibs 6 with the side walls of body 1 form a resilient gripping structure for gripping the compact plate 55 7. This plate has been shown with an inclined wall 8, but the nibs 6 will coact with a straight wall, or in fact, with plates formed without walls.

By providing the pressed-out portions 4 grooves 9 are provided, and into these grooves may be inserted nail files, scissors or other implements which are brought to bear against the plate 7 so as to eject the same when desired. The pressed-out portions 4 are preferably formed when the body 1 is formed, and if desired, could be formed by the same die, though they may be formed in any desired manner. The intention is to provide grooves which will not be objectionable in appearance 70 and which will permit an ejecting tool of some kind to be inserted below the plate 7 or at a point near the lower edge, whereby the plate may be engaged and lifted out of body 1. This is necessary when a new compact is 75 to be inserted after the former one has been exhausted. Also, in stores it is not unusual for a purchaser to desire a different kind of powder in a vanity case, and consequently, the filled compact plate must be removed. If the compact is broken or cracked in removal, it is more or less unsalable. By providing one or more grooves 9 a tool may be inserted so that the compact may be engaged 80 rather than the powder, and consequently, the plate and powder may be removed without scratching or otherwise injuring the powder.

In Figures 4 and 5 a modified structure is shown wherein the body 1 is provided with nibs or spurs 6' which act in the usual way of devices of this kind and identical with the way outlined in my prior Patent No. 1,209,168. Arranged at convenient points in the body 1 are pressed-out portions 10 and 11. Two of these pressed-out portions have been shown, but it is evident that more could be used, or if preferred, one could be used. These pressed-out portions are at points 95 spaced from the various nibs 6' so that the 100 102

respective grooves 12 formed by the pressed-out portions extend down to the bottom or near the bottom of the body 1, as shown in Figure 5. In this way the nail file, scissors or other implement may be readily forced beneath the plate 7 so as to eject the plate and its contents. It will be understood that the grooves 12 may be made of any width and preferably to the bottom of the body 1. On the outside of the body 1 the pressed-out portions 10 and 11 form beads which are more or less ornamental, and which are covered by suitable pressed-out portions 10' and 11' on the cover 2'. The same is true of the preferred form, cover 2 being provided with pressed-out portions which overlap the pressed-out portions 4.

In Figure 6 another form of the invention is shown wherein groove 12' extends from the bottom to the shoulder 13, said shoulder being of the usual formation so that the upstanding wall of the cover may fit thereof in the usual manner. This arrangement secures the same result as the other forms of the invention but does not necessitate the pressed-out portions 10' and 11', as shown in Fig. 4. An instrument 14, as for instance, a pair of scissors or a nail file may be readily inserted and the compact plate ejected. It is, of course, understood that this arrangement may be used in connection with the structure shown in Figure 3, that is, the groove 12' could be made to extend to the nibs 6 or to extend to the bottom of the body of the compact, as shown in Fig. 6.

What I claim is:

1. A vanity case, including a metallic body formed with an upstanding wall, said wall being provided with indented portions presenting nibs for holding a compact plate in the body and with grooves extending from the top edge downwardly, whereby a tool may be inserted to a position for engaging the compact plate without engaging the powder cake carried thereby.

2. A vanity case, including a metallic body having an upstanding wall, said wall being provided with a groove extending toward the bottom sufficiently far to permit a tool to be inserted to a position for engaging the compact plate carried by the body without engaging the powder cake carried by the plate, whereby said plate may be ejected.

3. A vanity case, provided with a body having a metallic upstanding wall, means carried by the body for holding a compact and compact plate in the body, said wall being provided with a groove extending from the top toward the bottom and of a sufficient size to permit the insertion of a tool to a position in engagement with said compact plate, whereby the compact plate may be ejected.

4. In a vanity case, including a body having a metallic upstanding wall formed with a groove extending from the top to the bot-

tom, and integral nibs for resiliently holding the compact plate in position, said groove being of a size to accommodate an implement of sufficient strength to engage and eject said compact plate.

5. A vanity case, including a body having a metallic upstanding wall formed with a compact plate holding nibs extending inwardly, and a groove extending from the top of the wall to the nibs, said groove being of a size to receive an implement capable of engaging and ejecting said plate.

6. A vanity case, including a body having a metallic upstanding wall, means carried by said wall for holding a compact plate in the body, said wall having a notch extending toward the bottom of the body for accommodating an ejecting tool.

7. A vanity case, including a body having a metallic upstanding wall formed with a groove extending from the top toward the bottom, said groove being arranged interiorly of the wall.

8. A vanity case, including a metallic body having an upstanding wall with a groove on the interior thereof extending from near the bottom toward the top.

9. A vanity case, including a bottom, a metallic upstanding wall formed with an offset for receiving the depending wall of a covering lid, an interiorly-positioned groove extending from said offset downwardly, said groove being of a size to admit the end of an implement so that a compact carried by the body may be readily ejected.

10. A vanity case, including a body, a metallic upstanding wall formed with a groove extending from a distance spaced downwardly from the top to substantially the bottom of the body, said groove being of a size to admit an implement, whereby the implement may be used to pry out or eject the compact plate carried by the body.

11. A vanity case, including a body having a metallic upstanding wall formed with a groove which extends from a point spaced from the top downwardly, said groove being of a size to admit the end of a compact plate ejecting implement.
